US0D1099657S

(12) **United States Design Patent** (10) **Patent No.:** **US D1,099,657 S**
(45) **Date of Patent:** **** Oct. 28, 2025**

(54) **BLADE**

(71) Applicant: **Hong Ann Tool Industries Co., Ltd.,**
Taichung (TW)

(72) Inventor: **Cheng-Wei Su**, Taichung (TW)

(73) Assignee: **HONG ANN TOOL INDUSTRIES**
CO., LTD., Taichung (TW)

(**) Term: **15 Years**

(21) Appl. No.: **29/844,694**

(22) Filed: **Jun. 30, 2022**

Related U.S. Application Data

(63) Continuation-in-part of application No. 17/325,609, filed on May 20, 2021, now abandoned, which is a continuation-in-part of application No. 16/665,247, filed on Oct. 28, 2019, now abandoned.

(51) **LOC (15) Cl.** **08-03**

(52) **U.S. Cl.**

USPC **D8/20**

(57) **CLAIM**

The ornamental design for a blade as shown and described.

DESCRIPTION

FIG. 1 is a perspective view of a blade showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines depict portions of the blade in which the design is embodied that are not considered part of the claimed design.

1 Claim, 7 Drawing Sheets
